US0D1067224S

(12) **United States Design Patent** (10) **Patent No.:** **US D1,067,224 S**
(45) **Date of Patent:** **** Mar. 18, 2025**

(54) **LAPTOP COMPUTER**

(71) Applicant: **LG ELECTRONICS INC.**, Seoul
(KR)

(72) Inventors: **Jihoon Shin**, Seoul (KR); **Youngho Kim**, Seoul (KR)

(73) Assignee: **LG ELECTRONICS INC.**, Seoul
(KR)

(**) Term: **15 Years**

(21) Appl. No.: **35/518,611**

(22) Filed: **May 18, 2023**

(80) **Hague Agreement Data**

Int. Filing Date: **May 18, 2023**
Int. Reg. No.: **DM/229421**
Int. Reg. Date: **May 18, 2023**
Int. Reg. Pub. Date: **Oct. 13, 2023**

(30) **Foreign Application Priority Data**

Dec. 30, 2022 (KR) 30-2022-0055515

(51) **LOC (15) Cl.** **14-02**

(52) **U.S. Cl.**

USPC **D14/315; D14/345**

(58) **Field of Classification Search**

USPC ..... D14/127, 138 R, 138 AB, 138 G,
D14/315-327, 341, 344-345, 371,

(57) **CLAIM**

The ornamental design for a laptop computer as shown and described.

DESCRIPTION

1. Laptop computer
- 1.1 : Top perspective
- 1.2 : Bottom perspective
- 1.3 : Front
- 1.4 : Back
- 1.5 : Left
- 1.6 : Right
- 1.7 : Top
- 1.8 : Bottom
- 1.9 : Top perspective
- 1.10 : Bottom perspective
- 1.11 : Front
- 1.12 : Back
- 1.13 : Left
- 1.14 : Right
- 1.15 : Top
- 1.16 : Bottom
- 1.17 : Top perspective
- 1.18 : Bottom perspective

(Continued)

1.19 : Front
1.20 : Back
1.21 : Left
1.22 : Right
1.23 : Top
1.24 : Bottom

The claimed design is a foldable laptop computer with a flexible touch display; reproductions **1.1** to **1.8** show a state of the claimed design folded; reproductions **1.9** to **1.16** show an alternate state of the claimed design partially unfolded; reproductions **1.17** to **1.24** show an alternate state of the claimed design fully unfolded; the broken lines shown in the reproductions depict portions of the laptop computer that form no part of the claimed design; the shading lines are used to show the surface of the claimed design and do not represent its surface ornamentation.

1 Claim, 24 Drawing Sheets
